UNITED STATES PATENT OFFICE.

JOHN B. MOSS, OF MORRIS, ILLINOIS.

SIDING-MARKER.

SPECIFICATION forming part of Letters Patent No. 678,269, dated July 9, 1901.

Application filed May 1, 1901. Serial No. 58,373. (No model.)

To all whom it may concern:

Be it known that I, JOHN B. MOSS, a citizen of the United States, residing at Morris, in the county of Grundy and State of Illinois, have invented a new and useful Siding-Marker, of which the following is a specification.

The invention relates to improvements in siding-markers.

10 The object of the present invention is to improve the construction of gages or devices for marking boards for cutting the same and siding a house and to provide a simple, inexpensive, and efficient siding-marker adapted 15 to make a clean-cut line across the siding and having the sharp edges of the blade arranged in the same plane as the gage-faces of the marker to enable a perfectly close joint to be made.

20 The invention consists in the construction and novel combination and arrangement of parts hereinafter fully described, illustrated in the accompanying drawings, and pointed out in the claims hereto appended.

25 In the drawings, Figure 1 is a perspective view of a siding-marker constructed in accordance with this invention. Fig. 2 is a detail view of a portion of the marker, illustrating the manner of mounting the slide. Fig. 3 is a transverse sectional view. Fig. 4 is a detail perspective view of the slide.

Like numerals of reference designate corresponding parts in all the figures of the drawings.

35 1 designates the body of the marker, composed of bars 2 and 3, preferably constructed of wood and forming the guide for a slide 4, which carries a blade 5. The bar 2 is provided at its ends with projecting arms 5, having inner flat faces 6 to fit against the corner board 7 of the structure and forming a recess 8 for the reception of a siding-board 9, the body being adapted to straddle the latter, as clearly illustrated in Fig. 1 of the accompanying drawings. The bar 3 is provided at its ends with projections 10, and it has an intervening recess 11, forming a longitudinal opening for the reception of the slide 4. The ends of the bar 3 are secured to the bar 2 by 45 screws 12 or other suitable fastening devices, and the said bar 3 is provided with a longi-

tudinal recess 13, located between the projections 10 and forming a thin inwardly-projecting rib or flange 14, which fits in a groove 15 of the slide 4. The slide 4, which consists 55 of a block, is provided near one end with the groove 15, which is sufficiently greater in width than the rib 14 to permit the slide to have an inward and outward movement for the purpose of carrying the blade 5 into and 60 out of engagement with the siding strip or board 9 and to withdraw the blade to a point within the longitudinal opening of the body. The outer portion of the block extends to the side face of the bar 3, and the inner end 16 of 65 the block is recessed or cut away adjacent to the groove 15, as clearly shown in Figs. 3 and 4, to receive the bar 3. The blade 5, which extends entirely across the block, is mounted in a recess thereof and is provided with a 70 beveled cutting edge which is curved or corrugated to form a series of projecting approximately segmental cutting portions 17, which are adapted when drawn across the face of a siding-board to make a clear sharp 75 cut. The outer face of the blade is flush with the adjacent face of the block and, as clearly shown in Fig. 3, is arranged in the same plane as the faces 6 of the projecting arms, so that the cut will enable a perfectly 80 close joint to be made.

It will be seen that the marker is exceedingly simple and inexpensive in construction, that it is conveniently operated, and that it is adapted to make a clean sharp cut and will 85 enable perfectly close joints to be made around windows and doors and at the corners and other portions of a structure.

What I claim is—

1. A device of the class described comprising 90 a body composed of the bar 2, provided with arms and the bar 3 having a longitudinal recess forming an opening, said bar 3 being also provided with a reduced portion or rib, a slide arranged in the said opening and 95 provided with a groove receiving the rib and permitting the slide to have an inward and outward movement, and a blade mounted on the slide and adapted to be carried into and out of the body by the movement of the slide, 100 substantially as described.

2. A device of the class described compris-

ing a body having an opening, a slide mounted in the opening and capable of a limited inward and outward movement, and a corrugated blade mounted on the slide and forming a series of segmental cutting portions, substantially as described.

In testimony that I claim the foregoing as

my own I have hereto affixed my signature in the presence of two witnesses.

JOHN B. MOSS.
